UNITED STATES PATENT OFFICE

2,603,021

COCKING MECHANISM FOR SHOTGUNS

Marcel Paulvé, Parmain, France, assignor of one-half to Societe Française des Munitions, de Chasse, de Tir et de Guerre (Anciens Etablissements Gevelot & Gaupillat), Societe Anonyme, Paris, France, a corporation of France

Application August 20, 1946, Serial No. 691,755
In France August 31, 1945

5 Claims. (Cl. 42—43)

1

This invention relates to sporting guns or rifles and more particularly contemplates the manufacture on an industrial scale of a gun or rifle which has heretofore been manufactured by empirical means by skilled craftsmen. Thus the barrels have been assembled by brazing or with tin solder. The same is true as regards the manufacture of the mechanism, in which geometrically shaped pieces and spring blades necessitate file finishing work.

The improvements forming the subject matter of the present invention provide for manufacture by means of a minimum of series produced mechanical parts, the assembly of which is simple and speedy, associated with simple coil springs in reduced numbers.

The present invention consists in a sporting gun or rifle of the kind comprising a frame and two barrels hinged thereto, having two sliding hammers, each of which are cocked by a spring compressed by the breaking and closing of the gun, and which are held in cocked position by sears. The front end of each hammer co-operates with an appertaining cocking cam pivotally mounted in a block which in turn is pivotally mounted on the rocking axis of the barrels and is rocked by the rocking of the barrels upon the opening and closing of the gun.

The cocking cams are pivotally mounted, within a single recess in the said block, on a hinged pin located parallel to the pivotal axis of the block. Each cam has an upper and a lower bevel, adapted to selectively engage a bevelled surface within the recess, whereby each of said cams may selectively occupy one of two positions according to the engagement of either of said two bevels thereon. When one of the bevels engages the surface within the said recess, in one of said positions, on the opening of the gun, each cam projects insufficiently beyond the edge of the block to move its appertaining hammer into engagement with its sear. Upon the closing of the gun, each cam is rocked into a second position, during the course of which movement it is projected sufficiently far to cock its hammer by engagement with its sear.

Hooks having circular recesses therein are provided on the two barrels, respectively, the said frame having two recesses disposed longitudinally of the frame and having disposed therein, about the rocking axis of the barrels, bushes which are adapted to be received in the circular recesses in the said hooks. The said bushes may be removable for the purpose of replacement.

The gun or rifle according to the invention is

2

provided with cartridge ejectors adapted for sliding movement in relation to the barrels, and movements transmitting levers for controlling the said ejectors, the said levers being mounted to rock within the block about the pivotal axis of the said cams. There is also provided a fixed element mounted in the said block, against which element the movement transmitting levers, towards the end of the rocking movement upon the opening of the gun, are adapted to bear so as to be slightly rocked about their axis for the purpose of advancing the cartridge ejectors to a certain extent sufficient to permit of extraction by hand of loaded or empty cartridge cases when located in the barrels.

The end of each transmitting lever opposite the end co-operating with its cartridge ejector is caused upon the opening of the gun to assume a position which is such that, when the appertaining cocking cam has been rocked to move back its associated hammer with compression of the hammer cocking spring and has moved past its furtherest projected position so that expansion of the said spring returns the said hammer suddenly forward, the forward end of said hammer impinges violently against the said lever for automatic ejection of the cartridge.

The forward end of each hammer carries a roller pivotally secured thereto and adapted to co-operate with its respective cocking cam for actuation thereby, and the forward end of each hammer is furnished with a sloping portion adapted to co-operate with its associated movement transmitting lever for actuation of its appertaining ejector.

The block is provided on its lower side with an abutment adapted, when the gun is opened, to bear against a bearing surface on the frame of the gun for the purpose of limiting the extent to which the barrels can be rocked.

Each hammer cocking spring is housed within an axial recess in its hammer and bears against the frame of the gun with its free end.

The closing of the gun may be insured by a bolt on the frame movable horizontally by a lever, and held in latched position by a spring, the lever being constructed in the form of an eccentric and adapted to be moved angularly in opposition to the spring for the purpose of actuating the said bolt.

In order that the invention may be more clearly understood, a preferred embodiment thereof will now be described by way of example with reference to the accompanying drawings in which:

Fig. 1 is a longitudinal vertical section of the mechanism of the gun, one hammer being shown in uncocked position;

Fig. 2 is a perspective view of the frame of the gun and appended parts;

Fig. 3 is a perspective view of the barrel assembly rotated through 180° from its position shown in Fig. 1;

Fig. 4 is an enlarged fragmentary longitudinal vertical section of the frame, showing the position of the parts when the gun has been opened fully;

Fig. 5 is a view similar to Fig. 4, showing the parts when one hammer is cocked and the gun is open;

Fig. 6 is a partial plan and horizontal section through the frame of Fig. 2.

The gun comprises a frame 1 to which is secured the stock. On a hinge-pin 2 of said frame, there is pivotally mounted a pair of barrels 3. A fore-part 4 which serves to hold the latches 3' of the barrels 3 in engagement with the hinge-pin 2 is itself held by a latch 6 against an assembly member 5 of said barrels 3. The latched condition of latch 6 is maintained by the action of a spring 7.

The above-described parts makes it possible to omit the hook which, in other types of guns, is usually soldered to the barrel in order to hold the fore-part.

Centrally the forward part of the frame 1 has a mortise 1^a. A block 8 disposed in said mortise 1^a is journaled on the hinge-pin 2 mounted in the frame 1. This block 8 controls the mechanism as a whole. It has a projection 8^a which fits in a slot 4' formed in the fore-part 4. The opening of the gun rocks the block 8 about the pin 2. The block 8 has an abutment 8' which limits the breakdown of the gun.

A pair of horizontal slots 9' formed in the frame receive the two hammers 9, respectively, which are slidably horizontally. Said hammers 9 effect percussion of the cartridges and ejection of the cartridge cases, moved forwardly by the action of their springs 10. The hammers 9 are held cocked by their sears 11, respectively, which are latched in the hammer catches 9^a by the springs 12.

At the right-hand side of Fig. 1 there is shown one trigger 13 which when actuated by finger pressure rocks its corresponding sear 11 which releases its hammer 9 which under the action of its spring 10, when the gun is closed, impinges against a cartridge placed in a barrel 3.

Two cams 14 are housed in a recess 8^b formed in the block 8 with parallel plane sides and a rear plane surface 8^c at an acute angle to the longitudinal axis of the block 8. Cams 14 actuate the hammers 9, respectively, through rollers 15 pivotally carried at the forward ends of the hammers 9, respectively.

Two transmitting movement levers 16 operating the extractors 18 are pivoted about the same axis as their cams 14, cams 14 and levers 16 being mounted on a hinge-pin 17 carried by the block 8 in its recess 8^b, and parallel with the hinge-pin 2. It should be noted that each cam 14 is provided on its lower forward end with an upper bevel 14^a and a lower bevel 14^b shown in dotted lines in Figs. 1, 4 and 5, so that each cam is adapted to bear selectively through either bevel 14^a or bevel 14^b against the rear plane surface 8^c of the recess 8^b housing the cams 14 in the block 8.

A cam 19 is mounted in the recess 8^b of the block 8 for a purpose hereinafter described.

The frame 1 has three recesses A, B and C (Fig. 2). The recess A which is the central mortise 1^a receives the block 8 and the parts carried thereby (that is the pair of movable cams 14, the pair of movement transmitting levers 16 and the fixed cam 19). The two side recesses B and C receive the barrel latches 3', respectively.

When the gun is opened, each cam 14 pushes back its hammer 9 through its roller 15. The cam 14 pushes its hammer 9 back as far as the point at which the cam 14 passes a line parallel with the line of movement of the hammer 9 and crosses the horizontal axis of the roller 15. In such position of the cam 14, the travel of hammer 9 is not long enough for the hammer 9 to engage its catch 9^a on its sear 11. As soon as the tip of the cam 14 has crossed the said axis of roller 15, said cam 14 is rocked upwardly (Fig. 4) and the end of hammer 9 returning forwardly impinges against its movement transmitting lever 16 which is mounted in the recess 8^b of the block 8 parallel with cams 14 and journaled on the hinge-pin 17. Movement transmitting lever 16 then transmits to its cartridge extractor 18 the momentum of the hammer 9 and causes ejection of the cartridge case (Fig. 4).

When the gun is being closed, the cam 14, which in its raised position illustrated in Fig. 4 bears through its upper bevel 14^a against the surface 8^c of the recess 8^b in the block 8 that encloses same, urges while said closing movement is being executed its hammer 9 back through a sufficient distance in order that its sear 11 may engage the hammer 9 through its catch 9^a provided for this purpose (Fig. 5). As the tip of the cam 14 crosses the horizontal axis of its roller 15, the cam 14 rocks downwardly (Fig. 5), leaving its hammer 9 engaged by its sear 11 in readiness for the firing of the freshly chambered cartridge.

It is obvious therefore that each cam 14 acts upon its hammer 9 to cam the same, in the opening movement of the gun, the displacement of hammer 9, however, being not sufficient to engage the hammer 9 with its sear 11, whereas the camming displacement, in the closing movement, does cause such engagement because the tip of the cam 14 moves toward and away from the axis of the hinge-pin 2 during the opening and the closing of the gun, respectively, by reason of its angular shifting. This is illustrated in Figs. 4 and 5 by radial broken lines R and r, respectively. It will be seen, Fig. 4, that line R indicating the distance from the axis of the hinge-pin 2 to the tip of the cam 14 when in its position during the closing movement is greater than line r (Fig. 5) indicating the distance from the axis of the hinge-pin 2 to the tip of the cam 14 when in its position during the opening. It will be noted (Figs. 1, 4 and 5) that the tip of the cam 14 is always positioned below a line drawn through the axis of the hinge-pin 2 and the axis of the hinge-pin 17, indicated in Figs. 4 and 5 by the broken line L.

If the gun is opened without the release of one of the hammers 9 having been initiated, its cam 14 remains in its lowered position so that its tip travels on an arc such that the cam 14 does not contact its roller 15 by reason of said cam 14 engaging the surface 8^c of the recess 8^b by its lower bevel 14^b. Consequently, said cam 14 does not move its hammer 9. Movement transmitting levers 16 are rocked by the fixed cam 19 (Fig. 5) and push out the cartridge extractors 18 a sufficient amount to enable the cartridges to be extracted by hand. Said cam 19 is housed in

the recess 8^b of the block 8 on the hinge-pin 2. It is held fast by a projection 19 on its lower portion and retained in a groove formed in the frame 1.

Closure of the gun is ensured by a single latch member 20 mounted on the frame 1, movable horizontally by the angular displacement of a key member 21, and held in latched condition by a spring 22. Said spring 22 is contained in a recess formed in the shank portion of the frame 1. Said latch 20, guided by a pair of lateral slideways, moves to engage the upper face of the end of the extension of the barrels 3.

The barrel latches 3' in recesses B and C are rotatable on bushing 2^a, respectively, in which extends the hinge-pin 2. Said bushings 2^a may be replaced when required so as to permit of taking up any amount of wear causing play.

I claim:

1. In an upward tilting breech double barrelled gun, the combination of a centrally mortised frame; two hammers adapted to slide longitudinally in said central mortise; springs urging said hammers forwardly; a barrel member mounted on a pivotal axis on the frame; a block movable with the barrel member, pivoted on said axis, facing the hammers and provided with a central flat recess bounded by parallel side planes and a rear plane surface at an acute angle to the longitudinal axis of said block, said recess opening towards the hammers; a pivot inside said recess perpendicular to said parallel side planes; a cam rockably secured to said pivot in front of each hammer and having a double-bevelled inner end, the tip of which cam lies underneath the line connecting said pivotal axis of the barrel member with said pivot, the cam being adapted to be shifted through cooperation with the end of the cooperating hammer between a lower position for which it engages through its lower bevel the angular rear surface of the recess and an upper position for which its upper bevel engages said angular rear surface, the engagement between the cam and the cooperating end of the corresponding hammer constraining the latter to move rearwardly through a certain length through the downwardly positioned cam upon opening of the gun and through a greater length through the upwardly positioned cam when the gun is being closed; a sear adapted to engage the hammer for holding it in its rearmost position produced by the cam during the closing of the gun; and means for releasing said sear to cause the operative movement of the hammer.

2. In an upward tilting breech double barrelled gun, the combination of a centrally mortised frame; two hammers adapted to slide longitudinally in said central mortise; springs urging said hammers forwardly; a barrel member mounted on a pivotal axis on the frame; a block movable with the barrel member, pivoted on said axis, facing the hammers and provided with a central flat recess bounded by parallel side planes and a rear plane surface at an acute angle to the longitudinal axis of said block, said recess opening towards the hammers, a pivot inside said recess perpendicular to said parallel side planes; a cam rockably secured to said pivot in front of each hammer and having a double-bevelled inner end, the tip of which cam lies underneath the line connecting said pivotal axis of the barrel member with said pivot, the cam being adapted to be shifted through cooperation with the end of the cooperating hammer between a lower position

for which it engages through its lower bevel the angular rear surface of the recess and an upper position for which its upper bevel engages said angular rear surface, the engagement between the cam and the cooperating end of the corresponding hammer constraining the latter to move rearwardly through a certain length through the downwardly positioned cam upon opening of the gun and through a greater length through the upwardly positioned cam when the gun is being closed; a sear adapted to engage the hammer for holding it in its rearmost position produced by the cam during the closing of the gun; means for releasing said sear to cause operative movement of the hammer; two transmitting levers pivotally secured to the pivot in the block, the lower ends of which levers are controlled when the gun is open by the movements of the hammers, respectively, when returned into their forward positions by their springs; and ejector mechanisms for the cartridges controlled by the upper ends of the transmission levers, respectively.

3. In an upward tilting breech double barrelled gun, the combination of a centrally mortised frame; two hammers adapted to slide longitudinally in said central mortise; springs urging said hammers forwardly; a barrel member mounted on a pivotal axis on the frame; a block movable with the barrel member, pivoted on said axis, facing the hammers and provided with a central flat recess bounded by parallel side planes and a rear plane surface at an acute angle to the longitudinal axis of said block, said recess opening towards the hammers; a pivot inside said recess perpendicular to said parallel side planes; a cam rockably secured to said pivot in front of each hammer and having a double-bevelled inner end, the tip of which cam lies underneath the line connecting said pivotal axis of the barrel member with said pivot, the cam being adapted to be shifted through cooperation with the end of the corresponding hammer between a lower position for which it engages through its lower bevel the angular rear surface of the recess and an upper position for which its upper bevel engages said angular rear surface, the engagement between the cam and the cooperating end of the corresponding hammer constraining the latter to move rearwardly through a certain length through the downwardly positioned cam upon opening of the gun and through a greater length through the upwardly positioned cam when the gun is being closed; a sear adapted to engage the hammer for holding it in its rearmost position produced by the cam during the closing of the gun; means for releasing said sear to cause operative movement of the hammer; two transmitting levers pivotally secured to the pivot in the block, the lower ends of which levers are controlled when the gun is open by the movements of the hammers, respectively, when returned in their forward positions by their springs; ejector mechanisms for the cartridges controlled by the upper ends of the transmission levers, respectively; and a cam rigid with the frame and adapted to urge the transmission levers when the gun is in its open position into positions so that they urge the ejecting mechanisms, respectively, slightly rearwardly.

4. In an upward tilting breech double barrelled gun, the combination of a centrally mortised frame; two hammers adapted to slide longitudinally in said central mortise; a barrel member

mounted on a pivotal axis on the frame; a block movable with the barrel member, pivoted on said axis, facing the hammers and provided with a central flat recess bounded by parallel side planes and a rear plane surface at an acute angle to the longitudinal axis of said block, said recess opening towards the hammers; a pivot inside said recess perpendicular to said parallel side planes; a cam rockably secured to said pivot in front of each hammer and having a double-bevelled inner end, the tip of which cam lies underneath the line connecting said pivotal axis of the barrel member with said pivot; transmitting levers pivotally secured to the pivot in the block; ejector mechanisms for the cartridges each controlled by the upper end of said corresponding transmission lever; a cam rigid with the frame and adapted to urge each transmission lever when the gun is in its open position into a position for which it urges its ejecting mechanism slightly rearwardly; a guiding rod rigid with each hammer and adapted to engage its corresponding rocking cam and the lower end of its corresponding transmission lever; a spring urging said rod into operative contact with said cam and the transmission lever and bearing against the frame, each rockable cam being adapted to be shifted through cooperation with the end of its corresponding hammer rod between a lower position for which it engages through its lower bevel the angular rear surface of the recess and an upper position for which its upper bevel engages said angular rear surface, the engagement between the cam and the cooperating end of its corresponding hammer rod constraining the latter to move rearwardly through a certain extent through the downwardly positioned cam upon opening of the gun and through a greater extent through the upwardly positioned cam when the gun is being closed the lever being shifted operatively by the hammer rod when the latter is urged forwardly by its spring; a sear adapted to engage each hammer for holding it in its rearmost position produced by the cam during the closing of the gun; and means for releasing said sear to cause operative movement of the hammer.

5. In an upward tilting breech double barrelled gun, the combination of a centrally mortised frame, two hammers adapted to slide longitudinally in said central mortise; springs urging said hammers forwardly; a barrel member mounted
